[57] **CLAIM**

The ornamental design for a housing for a modular electrical switch, receptacle device or the like, substantially as shown and described.

DESCRIPTION

FIG. 1 is a perspective view of a housing for a modular electrical switch, receptacle device or the like showing our new design, the broken lines being shown for illustrative purposes only and forming no part of the claimed design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and

FIG. 7 is a bottom plan view thereof.

The switch in FIG. 1 and the electrical receptacle in FIG. 6 have been shown in broken lines for illustrative purposes only and form no part of the claimed design.

FIG.-1.FIG.-2.FIG.-3.FIG.-4.FIG.-5.FIG.-6.FIG.-7.
